UNITED STATES PATENT OFFICE.

FRANK J. KOTZICH, OF CHICAGO, ILLINOIS, ASSIGNEE TO A. STEIN & COMPANY, OF CHICAGO, ILLINOIS, A CORPORATION.

CLASP.

1,189,191.

Specification of Letters Patent. Patented Sept. 26, 1916.

Application filed February 24, 1916. Serial No. 80,129.

To all whom it may concern:

Be it known that I, FRANK J. KOTZICH, a subject of the Emperor of Austria-Hungary, residing in Chicago, county of Cook, and State of Illinois, have invented certain new and useful Improvements in Clasps, of which I do declare the following to be a full, clear, and exact description, reference being had to the accompanying drawing, forming a part of this specification.

The present invention has for its object to provide an improved clasp formed of metal with a covering of flexible material and a novel method of manufacturing said clasp, and the invention consists of the features of improvement hereinafter described, illustrated in the accompanying drawing and particularly pointed out in the claims at the end of this specification.

Figure 1 is a perspective view of an arm band showing my improved clasp applied thereto. Fig. 2 is a view of the body of the arm band showing one way in which its ends may be connected together before my improved clasp is applied thereto. Fig. 3 is an enlarged end view of the clasp inclosing the ends of the band bent to clamping position. Fig. 4 is a view of a covered metal strip from which my improved clasp will be formed. Fig. 5 is a perspective view of my improved covered clasp ready for use. Fig. 6 is an enlarged view in cross section through my improved clasp.

Referring to the accompanying drawing, A designates the body of an arm band that may be formed of elastic material, B denotes a metal clip by which the ends of the elastic band A are joined together, and C denotes a bow of ribbon, or like ornamental material, that may be placed over the united ends of the elastic band A before my improved covered clasp D is applied thereto.

The body portion 8 of my clasp consists of a metal strip that has a covering 9 of flexible material such, for example, as silk or other fabric. The covering 9 of flexible material encircles the metal body 8 of the clasp and the edges of this covering may abut or slightly overlap at the center. Preferably, the lapping edges of the flexible covering are united by a suitable paste or glue or the paste or glue may be applied to

the inner surface of the body 8 of the clasp at the time that the covering is applied thereto.

In forming my improved clasp, I take a long strip of thin metal (such as tin plate or brass) and apply thereto a covering of flexible material, as shown in Fig. 4 of the drawing, the edges of the flexible covering being brought together at the center of the strip and united together or to the strip by paste or glue. The strip with the flexible covering thereon is then cut into blanks of suitable length, as indicated by dotted lines in Fig. 4. After the covered strip has thus been cut into blanks, the covered blanks will have their ends 10 folded over, as shown in Figs. 5 and 6, and the body of the blanks will be bent to give to them a U-shaped or channel form. After the blanks of the clasp have thus been folded and bent, they may be placed about the article in connection with which they are to be used. Thus, when my improved blank is to be used about the joined ends of an arm band, as illustrated in the drawing, the U-shaped clasp shown in Figs. 5 and 6 will be placed over the joined ends of the arm band (see Fig. 2) the bow or ornamental loop C (if such be used) being first placed within the crown of the clasp, after which the folded ends of the clasp will be brought together around the joined ends of the arm band, as shown in Fig. 3. By folding the ends 10 of the blanks, as indicated in Figs. 5 and 6, the flexible covering will be securely retained against danger of displacement and a very neat and durable clasp is thus provided.

While I have shown my improved clasp as applied to an arm band, it will be readily understood that it may be used in a variety of other situations in which a covered clasp may be desired for joining, protecting or ornamenting various articles. When used with devices, such as an arm band, on which it would be objectionable to have a clasp of metal, the covering of flexible material not only serves to give a more attractive appearance to the clasp but protects the metal and also protects the garments of the wearer from contact with metal, which would be objectionable.

Having thus described my invention, what

I claim as new and desire to secure by Letters Patent is:—

1. A clasp of the character described, comprising a metal body having a covering of flexible material, the end portions of the clas being folded over with the clasp covering between the end folds of the metal and the body of the clasp being bent between its folded ends.
- 10 2. A clasp of the character described, comprising a metal body having a covering of flexible material, the edges of said flexible

covering being disposed upon the inner side of the metal body and the end portions of said clasp being folded over with the flexible 15 material between the folds.

3. The combination with joined fabric ends and with suitable means for uniting said ends together, of a clasp encircling said joined ends comprising a metal body having a flexible covering, the end portions of said body being folded over with the flexible covering between the folds.

FRANK J. KOTZICH.
